UNITED STATES PATENT OFFICE.

PETER KUCERA, OF SOUTH CONNELLSVILLE, PENNSYLVANIA, ASSIGNOR TO CAPSTAN GLASS COMPANY, OF SOUTH CONNELLSVILLE, PENNSYLVANIA, A CORPORATION OF DELAWARE.

APPARATUS FOR ASSEMBLING CELLULAR FORMS.

1,374,454.

Specification of Letters Patent. Patented Apr. 12, 1921.

Application filed May 21, 1920. Serial No. 383,140.

To all whom it may concern:

Be it known that I, PETER KUCERA, a citizen of the United States, and a resident of the city of South Connellsville, in the county of Fayette, State of Pennsylvania, have invented certain new and useful Improvements in Apparatus for Assembling Cellular Forms, of which the following is a specification.

This invention relates to the manufacture of cellular boxes, and pertains particularly to a novel method and means for facilitating the assembly of separate blanks or partition strips into interengaging association to provide the cellular partition forms commonly employed in various kinds of packing and shipping cases.

As is well known in the art, in the manufacture of cellular boxes, it is customary to provide a plurality of cellular blanks in the form of partition strips, which are cut to proper dimensions and slotted or notched, and then assembled with halved joints, so that they coöperate to provide partitions for a plurality of cells. In various forms of packing cases these partition strips are formed of strawboard, corrugated paper, thin veneer, and other flexible materials and, in present practice, are assembled customarily by hand, in the establishment where the case is to be filled, rather than in the establishment where the materials for the case are formed. This is a costly process due to the amount of time required to properly fit the slotted strips together.

The general object of the present invention is the provision of a simple and economical method and apparatus which may be conveniently employed in an establishment, not directed primarily to the manufacture of the cases, for the purpose of assembling the ready cut and knocked down portions of a cellular partition form into their proper relationship for insertion into the cases or containers in which they are employed.

It is also an object of the invention to provide such an appliance which will greatly expedite and simplify the assembling of such articles, so that they may be put together very rapidly by a person having no special skill or practice in the work, and thus secure a great reduction in operating cost.

Other and further objects and advantages

of the invention will be pointed out herein-after or indicated in the appended claims, or be obvious from the accompanying drawings in which an illustrative embodiment of the invention is shown.

In the drawings Figure 1 represents a top or plan view of the assembling rack or table;

Fig. 2 is a sectional elevation taken substantially on line 2—2 of Fig. 1; and

Fig. 3 is an illustration of a cellular partition form of the kind assembled on the illustrated device.

By reference to these drawings it will be understood that the invention contemplates the provision of a suitable support which may be in the form of a table 1, and above which are disposed in predetermined relationship, series of guide and spacing members 2. These members present supporting portions or walls 2^a and guide portions 2^b. In the form illustrated the members 2 are in the nature of rectangular entities supported on the table with their vertically disposed walls forming the supporting portions 2^a and with their horizontal edges chamfered or beveled off to provide the guide portions 2^b sloping downwardly toward the supporting portions 2^a. The spacing members are disposed with their supporting portions 2^a in alinement and with the opposed supporting portions 2^a on adjacent spacing members spaced apart a proper distance to accommodate the thickness of the intended partition strips. The guide portions 2^b on the adjacent spacing members thus disposed coöperate to afford grooves having comparatively wide mouths and converging toward the supporting portions 2^a. The several spacing members having their supporting portions disposed in rectangular relationship, they will form, when disposed in the intended association, a plurality of rectangular intersecting slots spaced apart by the width of the spacing members. The horizontal dimensions of the spacing members between opposite supporting portions 2^a being the horizontal dimensions of the intended cells, the spacing of the parallel slots will coincide with the spacing of the slots or notches in the pre-formed partition strips. One of such partition strips is illustrated in fragmentary elevation in

Fig. 2, where it is designated by the char-

acter S, and others of such strips are designated in said figure by the character S', the slots in such strips being designated by the character S². Along the adjacent sides of 5 the associated group of spacing members are disposed stop members 4 which are effective to close the ends of the slots or channels between the spacing members. At suitable intersections of such slots or channels 10 lifting members 5 are associated with the support 1 in such fashion that they may be moved vertically in the slots. Mechanism for operating the lifting members in such fashion may include a frame 6 carried on 15 a member 7 slidably supported in a guide 8, and a suitably operated lever 9 coöperating with the member 7 so that upon swinging of the lever the member will be slid upwardly through the guide 8, to project 20 the lifting members 5 upwardly between the spacing members.

In operation of the device, the operator being supplied with the suitable blanks to make the cellular form, for example, as illustrated in Fig. 3, he places the necessary number thereof in the parallel grooves afforded by the associated spacing members, with the slots or notches in the strips presented upwardly. This may be accomplished very rapidly, the operator utilizing both hands simultaneously to place different strips, the proper seating of the strips being facilitated by the tapering grooves provided by the sloping guide faces 2^a. 25 When disposed in the slots, the partition strips will be held on edge in proper upright position by the supporting faces 2^a, and the registry of the slots S² with the intersecting channels will be insured by contact of the ends of the partition strips against the stop members 4. Other partition strips are then slipped downwardly into the grooves traversing the strips originally positioned, the notched edges of the second 30 series of strips being inserted first. Due to the fact that the original partition strips are held in definite relationship, strips of the second series may be applied directly in proper position without the necessity for 35 the moving, bending or forcing of any of the strips. The form thus having been assembled, the lever 9 is operated to raise the lifting members 5 which elevate the form as a unit out of the slots between the spacing 40 members.

An apparatus having the essential characteristics of that above described is of particular utility in the assembling of cellular forms in which the partition strips are of 45 flexible or pliable material such as straw-board, corrugated paper and the like, as the guide portions of the spacing members co-operate effectively to straighten and direct the partition strips in proper positions, 50 while the supporting portions 2^a are effective

to maintain the strips in alignment and sustain them in the operation of halving the intersection strips.

It is obvious, of course, that the invention is susceptible of embodiment in a great variety of forms differing in detail and arrangement, and it is to be understood, therefore, that the scope of the invention is to be determined from the following claims, and not from the illustrative species above described.

Having thus described my invention, what I claim is:

1. A device for assembling cellular partition forms comprising the combination of 80 a support, spacing members associated therewith to sustain a plurality of partition strips in parallel relationship, said spacing members including supporting portions disposed for coöperation with partition strips 85 extending in angular relationship, said spacing members including guide portions arranged to direct partition strips into association with the supporting portions.

2. A device for assembling cellular partition forms comprising the combination of a support, spacing members associated therewith to sustain a plurality of partition strips in parallel relationship, said spacing members including supporting portions disposed for coöperation with partition strips 90 extending in angular relationship, said spacing members including guide portions arranged to direct partition strips into association with the supporting portions, and 95 means associated with the support and spacing members for simultaneously removing spacing strips in assembling relationship from association therewith.

3. A device for assembling cellular partition forms comprising the combination of a support and spacing members arranged to sustain partition strips, said spacing members having supporting portions spaced apart and coöperating to afford slots for the 105 reception of partition strips, said spacing members including guide portions coöperating with the supporting portions to facilitate the insertion of spacing strips edgewise into such slots, there being stops for determining the longitudinal position of partition members in such slots, and divers of the supporting portions being disposed in angular relationship to afford intersecting 110 slots.

4. In a device for assembling cellular partition forms, the combination with a support of a plurality of spacing members including supporting portions arranged to provide series of intersecting slots for the 125 reception of partition strips, the supporting portions forming aligned walls which are continuous excepting at the intersection of slots, and there being guide portions co-operating with the supporting portions to 130

facilitate the insertion of partition strips edgewise between the latter.

5. In a device for assembling cellular partition forms, the combination with a support of a plurality of spacing members including supporting portions arranged to provide series of intersecting slots for the reception of partition strips, the supporting portions forming alined walls which are continuous excepting at the intersection of slots, there being guide portions coöoperating with the supporting portions to facilitate the insertion of partition strips edgewise between the latter and means for determining the longitudinal positions of partition strips in the slots relative to intersecting slots.

6. In a device for assembling cellular partition forms, the combination with a support of a plurality of spacing members including supporting portions arranged to provide series of intersecting slots for the reception of partition strips, the supporting portions forming alined walls which are continuous excepting at the intersection of slots, there being guide portions coöoperating with the supporting portions to facilitate the insertion of partition strips edgewise between the latter, and means movable relative to the spacing members for engaging associated partition strips and removing them from the slots in assembled relationship.

7. A device for assembling cellular partition forms comprising a table provided with rectangularly intersecting series of parallel slots, the sides of the slots pro-

viding coöperating supporting members adapted to sustain partition strips with their edges presented toward the mouths of the slots, there being guide portions formed by sides converging to the several slots, and stops for determining the longitudinal positions of partition strips in the slots.

8. A device for assembling cellular partition forms comprising a table provided with rectangularly intersecting series of parallel slots, the sides of the slots providing coöperating supporting members adapted to sustain partition strips with their edges presented toward the mouths of the slots, there being guide portions formed by sides converging to the several slots, stops for determining the longitudinal positions of partition strips in the slots, and means for ejecting associated partition strips from the slots in assembled relationship.

9. A device for assembling cellular partition forms comprising the combination of a support, spacing members associated therewith and having supporting portions disposed in angular relationship, the supporting portions on divers spacing members coöperating to sustain partition strips in definite relationship on edge, guide portions for directing partition strips edgewise into association with the supporting portions, and means associated with the support for removing assembled spacing strips collectively from association with the spacing members.

PETER KUCERA.
